(57) **CLAIM**

I claim the ornamental design for a display bracket for use with mounting systems for audio/visual devices or the like, as shown and described.

DESCRIPTION

FIG. 1 is a perspective view of a display bracket for use with mounting systems for audio/visual devices or the like showing my new design;

FIG. 2 is a front elevational view therof;

FIG. 3 is a rear elevational view therof;

FIG. 4 is a right side elevational view therof;

FIG. 5 is a left side elevational view thereof; and,

FIG. 6 is a top plan view thereof, the bottom plan view being identical to the top plan view.

The broken lines shown are for illustrative purposes only and form no part of the claimed design.
